Filed June 1, 1965, Ser. No. 85,523

Term of patent 14 years

(Cl. D87—2)

FIG. 1

FIG. 2

FIG. 3

FIG. 6

FIG. 4

FIG. 7

FIG. 8

FIG. 5

FIG. 1 is a top plan view of a luggage drawbolt showing my new design, in fully open condition;

FIG. 2 is a side elevational view thereof;

FIG. 3 is a top plan view of the drawbolt in closed condition, on a reduced scale;

FIG. 4 is a side elevational view thereof;

FIG. 5 is a bottom plan view thereof;

FIG. 6 is a right end elevational view thereof;

FIG. 7 is a left end elevational view thereof; and,

FIG. 8 is a view similar to FIG. 7, but showing the drawbolt in partially opened condition.

The characteristic feature of my design resides in the combination on the drawbolt disclosed of co-acting base members which in latched condition provide a planar peripheral flange having an arcuate forward portion and an elliptical rearward portion and a loophasp indented from and parallel to the outline of said base flange, all as shown.

I claim:

The ornamental design for a luggage drawbolt, as shown and described.
